United States Patent Office

Des. 218,453

Patented Aug. 18, 1970

218,453

GAME BOARD

Helen P. Lasker, 94-01 64th Road,
Rego Park, N.Y. 11374

Filed May 28, 1969, Ser. No. 17,392

Term of patent 7 years

Int. Cl. D21—01

U.S. Cl. D34—5

Fig. 1.

Fig. 2.

FIG. 1 is a top perspective view of a game board embodying my new design, and

FIG. 2 is a side end view looking in the direction of arrows 2—2 thereof.

I claim:

The ornamental design for a game board, substantially as shown.
